UNITED STATES PATENT OFFICE.

ARVID PETERSON, OF TRENTON, NEW JERSEY, ASSIGNOR TO DE LAVAL STEAM TURBINE COMPANY, OF TRENTON, NEW JERSEY, A CORPORATION OF NEW JERSEY.

DRIVING GEAR.

Application filed July 29, 1921. Serial No. 483,307.

To all whom it may concern:

Be it known that I, ARVID PETERSON, a citizen of the United States, residing at Trenton, county of Mercer, and State of New Jersey, have invented a new and useful Improvement in Driving Gear, of which the following is a full, clear, and exact description, reference being had to the accompanying drawings, which form a part of this specification.

This invention relates to an improvement in driving pinions and particularly wide face, heavy duty pinions, such as high speed gear reduction pinions in large power plants.

In pinions of this character, it is very essential that the load to the pinion should be uniformly distributed without distortion of the pinion, as such distortion will cause uneven contact between the teeth on the driving pinion and the teeth on the driven gear, and will also cause a variation in contact due to load conditions.

The object of my invention is to provide a pinion in which this distortion will be materially reduced. I accomplish this by providing a pinion which is so constructed that it acts when under a load in a manner substantially the same as a pinion under a load which is driven from both ends with substantially one-half the power being transmitted through each end of the pinion. In designing a pinion, I first calculate the distortion due to the twist caused by the load on the pinion, and then provide a pinion having a twist relative to the gear equal substantially to one-half the twist to which the pinion is subjected when under substantially the maximum load, and in the reverse direction to the twist caused by the load. The pinion is relatively twisted in such a manner that the faces of the engaging teeth of the pinion at the end opposite the driven end of the pinion are in engagement with the teeth of the driven gear, while the faces of the teeth at the driven end of the pinion are clear or substantially free of the teeth of the driven gear when the pinion is running light or without load. The precise nature of my invention will be best understood by reference to the accompanying drawings, which will now be

described, it being premised, however, that changes may be made in the form of the structure without departing from the spirit and scope of my invention as defined in the appended claims.

Fig. 1 of the drawings is a diagram of a herring-bone pinion driven from one end, together with a graduated curve chart illustrating the distortion of the pinion at different points, and a diagram of a similar pinion to illustrate the effect if driven from both ends.

Fig. 2 is a longitudinal sectional view through one form of pinion constructed in accordance with my invention, and a portion of a gear driven thereby.

In calculating the amount of distortion due to twist, it is assumed that the torque diminishes gradually from the coupling end of the pinion towards the free end and that the pinion is free to move endwise so that each helix takes its share of the load.

The formula for calculating the distortion due to twist is obtained from Hutt's Engineers Pocket Book, Vol. I, pages 570, 571 and is as follows

$$\delta = \frac{32 T}{\pi d^4 G} \quad 80$$

where

δ =relative angular displacement of two sections in inches at 1" radius and 1" apart

d =diameter of shaft inches. 85

$$T_x = \frac{TX}{L}$$

and the distortion of two sections dx'' apart. 90

T =torsional moment in inch lbs.

G =modulus of rigidity 12×10^6 for steel.

Taking now a pinion P and curve p as shown in Fig. 1 driven from the right hand side, the moment at a section x is 95

$$dy = \frac{T \cdot x \cdot 1.32}{L \cdot G \cdot \pi d^4} \cdot \frac{d}{2} dx$$

$$dy = \frac{T \cdot 16}{L \cdot G \cdot \pi d^3} \cdot x dx \quad 100$$

or the distortion at any point x

$$y = \frac{T \cdot 16 \cdot x^2}{L \cdot G \cdot \pi d^3 \cdot 2} \quad 105$$

Taking as an example a pinion transmitting 3000 H.P. at 3600 R.P.M. of the following dimensions—

5 Pitch diameter $d=7.8''$.
Total width face $1=34''$
we have

$$T = 63025 \frac{3000}{3600} = 52500 \text{ inch lbs.}$$

10 and

$$y = \frac{52500 \cdot 16 \cdot x^2}{34 \times 12 \times 10^6 \cdot \pi \cdot 7 \times 8^3 \times 2}$$

$$y = \frac{X^2}{144.8 \cdot 10^4}$$

15 Accordingly the distortion at C for $X=34$

$$y = \frac{1156}{144.8 \cdot 10^4} = \frac{8}{10^4} = .0008$$

20 and at B for $X=17$

$$y = \frac{289}{144.8 \cdot 10^4} = \frac{2}{10^4} = .0002$$

In other words there would be an opening of contact at B on the right hand helix of .0008—.0002=.0006", resulting in heavy load at C and on the left hand helix there would be an opening of contact at A of .0002 resulting in heavy load at B on this helix.

30 The curve P drawn up shows the distortion at different points of the pinion.

Now, if it were possible to drive the pinion from both ends as at P', with half the power going into each end, the distortion due to 35 twist will be diminished materially in the right hand half.

The figures below will show this. We now have

$$40 \quad \frac{T}{2} = 26250 \text{ inch lbs.}$$

going into each end, and the length subjected to twist is now

$$45 \quad \frac{1}{2} = 17''$$

so that

$$y_1 = \frac{26250 \times 16 \times 17^2}{17 \times 12 \times 10^6 \times \pi \times 7 \times 8^3 \times 2} = .0002''$$

50 Accordingly the distortion in each helix will now be only .0002" as shown by curve p' compared with .0006" before, in the right hand helix or a reduction in distortion of one third.

55 In the left hand helix the amount of distortion will naturally be the same as before.

The results from a pinion constructed in accordance with my invention, if driven from the right hand end, will be substantially the same as a pinion driven from both ends as the pinion P' of Fig. 1.

The pinion illustrated in Fig. 2 comprises a sleeve or hub g having two sets of helical teeth h thereon, a flange j at the driven end 60 and a similar flange k at the other end.

Passing through the hub g is a quill shaft f , having an integral flange m at one end, which is connected to a coupling member n on the drive shaft o , and the flange j on the shaft, by a pin p .

70 r is a flanged collar or connecting member secured to the other end of the quill shaft, and is secured to the flange k on the hub of the pinion by means of a pin s . The collar r is keyed to a frusto-conical seat on the quill shaft and is held to said seat by a nut t . w is a gear wheel having two sets of teeth which mesh with the teeth on the pinion.

75 In order to transmit substantially the same load through each end of the pinion, I first calculate the twist caused by the load to be driven by the pinion, then lay out and form the holes in the different members for the coupling pins, twist the shaft f and couple. The twisting of the shaft to the proper degree will align the various holes for the pins, and when coupled the pinion will be under substantially one-half the twisting stress to which the pinion is subjected when under its normal load, but which twist is in the reverse direction to the twist caused by the load. When the shaft o is rotated and the pinion is under the normal load, the effect will be the same as if the pinion were driven at both ends with equal power. If desired, the twist caused by the load may be determined by test, and the pinion and gear may then be made in accordance with such test.

80 The advantages of my invention result from the provision of a pinion and the method of making a pinion having a twist therein which will cause the teeth on the opposite ends thereof to contact with the teeth on the gear wheel driven thereby when the gearing is under load; whereby I am enabled to use standard pinions and gears having parallel teeth, and then twist the pinion to meet the specified requirements of the driving mechanism.

85 A further advantage results from the fact that the quill shaft will form a flexible connection between the driving motor and the driven gear, which will assist in absorbing sudden shock transmitted through the train of gears driven by the motor.

90 Having now fully described my invention, what I claim and desire to protect by Letters Patent is:

95 1. The combination of a driving pinion and a shaft secured to each other, one of said members being under a twisting strain when not under load in a direction to substantially relieve the strain when driving the normal load calculated to be driven thereby.

100 2. A driving element having two sets of helical teeth on a sleeve member, the teeth of one set extending in an opposite direction

to the teeth of another set, a quill shaft extending through the sleeve member means for connecting the sleeve member to the shaft in such a manner that both sets of teeth are between said connection, and means for coupling in driving relation one end of the shaft to a power transmitting member,

the shaft and sleeve being twisted relative to each other in a reverse direction to a twist caused by a load.

10

In testimony of which invention, I have hereunto set my hand, at Trenton, N. J., on this 27th day of July, 1921.

ARVID PETERSON.
